L. ANDERSEN & M. HANSEN.
DOOR LOCK GUARD.
APPLICATION FILED JULY 31, 1908.

913,800.

Patented Mar. 2, 1909.

UNITED STATES PATENT OFFICE.

LUDVIG ANDERSEN AND MARTIN HANSEN, OF NEW YORK, N. Y.

DOOR-LOCK GUARD.

No. 913,800.

Specification of Letters Patent.

Patented March 2, 1909.

Application filed July 31, 1908. Serial No. 446,262.

To all whom it may concern:

Be it known that we, LUDVIG ANDERSEN and MARTIN HANSEN, subjects of the King of Norway, and residing at New York, in the 5 county of New York and State of New York, have invented certain new and useful Improvements in Door-Lock Guards, of which the following is a specification, such as will enable those skilled in the art to which it app- 10 pertains to make and use the same.

This invention relates to door lock guards of the class known as key hole protectors and which consist of a metal plug or case resembling in shape, in cross section, the shank 15 and bit of a common key, and which, is adapted to be inserted into the key hole of a lock and fastened therein, and which is designed to prevent the opening of the door or the "picking" of the lock from either side, 20 the said device being provided with means operated by a key for securing it in the lock.

The invention is fully disclosed in the following specification, of which the accompanying drawing forms a part, in which the 25 separate parts of our improvement are designated by suitable reference characters in each of the views, and in which;—

Figure 1 is a vertical section of a part of a door taken through the casing of the lock 30 and through the key hole or holes and showing our improved lock guard in position for use. Fig. 2 a sectional side view of the lock guard on a larger scale and showing a key in position to be inserted thereinto; Fig. 3 a 35 diagrammatic view showing the casing of the lock guard in dotted lines and showing the tumblers thereof in full lines, and showing a key in position to operate the tumblers; Fig. 4 a transverse vertical section on the line 40 4—4 of Fig. 2; and, Fig. 5 a plan view of a bolt or plug which forms a part of the lock guard.

In the drawing forming part of this specification, we have shown at *a* a part of a door 45 and in which is secured the ordinary lock casing *b*, the mechanism of the lock being not shown, and said door is provided at its opposite sides with the usual key holes *c* which are provided with the usual escutcheon 50 plates *c*².

In the practice of our invention, we provide a lock guard *d* adapted to be inserted into one of the key holes from either side of the door, and said guard consists of a case, 55 comprising a horizontal top tubular member *d*² and a depending bit member *d*³, the said

case resembling in vertical transverse section, the shank and bit of an ordinary key. The case of the lock guard is preferably composed of two parts, as shown in Fig. 4, riveted 60 together as shown at *d*⁴, and the transverse top member *d*² thereof is provided with a tubular bore *d*⁵, and the depending bit member *d*³ of said case is provided with a chamber *d*⁶ in which are pivoted two rock- 65 ing tumblers *e* and *f*, said tumblers being pivoted respectively at *e*² and *f*², and said tumblers are normally held in a horizontal position, the top tumbler *e* being provided at its opposite ends with upwardly directed 70 noses or projections *e*³ and *e*⁴, and the bottom tumbler *f* being provided at its opposite ends with upwardly directed projections or noses *f*³ and *f*⁴. A spiral spring *g* is placed between the tumblers *e* and *f* at one end thereof, 75 and beneath the opposite end of the tumbler *e* is placed a stop *g*², and beneath the end of the bottom tumbler *f* over which the spring *g* is placed is another stop *g*³. We also provide a plug or bolt *h* which is adapted to be 80 passed through the tubular top portion of the lock guard as shown in Figs. 1 and 2, and which is provided with an annular groove *h*² and is held in place by a screw *h*³ passed through the top of the case of the lock guard 85 and into said groove, and said plug or bolt is adapted to be operated by a key *i*. The plug or bolt *h* is provided within the top portion of the case of the lock guard, when said plug or bolt is in position, with two annular grooves 90 *h*⁴ and *h*⁵, and one end of said plug is provided with a head *h*⁶, and the end of the plug or bolt *h* in which the grooves *h*⁴ and *h*⁵ are formed is provided with a longitudinal slot *h*⁷, and the end of the plug or bolt *h* 95 opposite the head *h*⁶ passes through the lock guard, and when said guard is in position as shown in Fig. 1, the said end of said plug or bolt projects approximately through the lock casing *b*, and that portion of the 100 plug or bolt *h* within the lock casing, when the guard is in position, is provided at one side with a radial pin *h*⁸.

The key *i* consists of a flat plate member *i*² provided at one end with a head or handle 105 *i*³, and the bottom edge of the plate member *i*² is provided adjacent to the end opposite the head *i*³ with a recess *i*⁴, and adjacent to the head end *i*³ with another recess *i*⁵, and between the recesses *i*⁴ and *i*⁵ is a longer 110 recess *i*⁶.

In the operation of this device, the guard

is inserted into one of the key holes as shown in Fig. 1, and in this operation the radial pin h^8 is turned down, as shown in dotted lines in Fig. 1, the key i being also inserted into the slot h^7 in the plug or bolt h as is also indicated in dotted lines in Fig. 1. The normal position of the tumblers e and f is shown in Fig. 2, but the position said tumblers assume when the key is inserted is shown in Fig. 3. After the guard has been inserted into the key hole as shown in Fig. 1, the key is turned through one-half a revolution and the bolt or plug h is turned so that the pin h^8 will be in the position shown in full lines in Figs. 1 and 2, and said pin will engage one of the sides b^2 of the lock casing b and the guard will be locked in the key hole and cannot be removed until the key i is again inserted and turned through a half revolution so as to throw the pin h^8 into the position shown in dotted lines in Fig. 1. In the normal position of the tumblers e and f , the nose or projection e^4 of the tumbler e enters the slot h^7 in the plug or bolt h as shown in Fig. 2, and the nose or projection f^3 of the tumblers f also enters said slot, and the said plug or bolt cannot be turned except by the key i , the insertion of which throws the said tumblers into the position shown in Fig. 3, and in this position the nose or projection e^3 of the tumbler e enters the groove h^4 in the plug or bolt h and the nose or projection f^4 of the tumbler f enters the groove h^5 of said plug or bolt, while the opposite noses or projections of said tumblers rest on the bottom edge of the key as shown in Fig. 3, and this permits the turning of the bolt or plug h by the key.

Our improved lock guard is simple in construction and operation, but can only be manipulated by the proper key, and when said guard is in the position shown in Fig. 1, the lock cannot be "picked" and the door cannot be opened except by a party provided with the key i .

Having fully described our invention, what we claim as new and desire to secure by Letters Patent, is;—

1. A lock guard comprising a case adapted

to be inserted into a key hole of the lock, and to fit therein, a bolt passed through the top portion of said case and rotatable therein, and provided within said case with two annular grooves, the end of said bolt within said case being also provided with a longitudinal slot, two rocking tumblers, pivoted in said case below said bolt, and provided at their opposite ends with upwardly directed noses or projections, one nose or projection at the end of each tumbler being adapted to enter the grooves in said bolt and the other noses or projections at the opposite ends of said tumblers being adapted to enter the slot in said bolt, a spring placed between said tumblers at one end thereof, stops for holding said tumblers in a normal position, and a key adapted to be inserted into the slot in said bolt, and to operate said tumblers and to rotate said bolt.

2. A lock guard comprising a case adapted to be inserted into the key-hole of a lock, a bolt passed through the top portion of said case, and secured therein, and rotatable therein, that part of said bolt within said case being provided with annular grooves, and with a longitudinal slot, pivoted tumblers mounted in said case below said bolt, and normally held in a horizontal position, said tumblers being provided at their opposite ends with upwardly directed noses or projections adapted to enter the slot in said bolt and at their other ends with upwardly directed noses or projections adapted to enter the annular grooves in said bolt, one end of said bolt being projected into the lock casing of the door and being provided with a radial pin, and a key adapted to be inserted into the slot in said bolt and to operate said tumblers and to rotate said bolt.

In testimony that we claim the foregoing as our invention we have signed our names in presence of the subscribing witnesses this 29th day of July 1908.

LUDVIG ANDERSEN.
MARTIN HANSEN.
